UNITED STATES PATENT OFFICE.

RUSSELL R. WADE, OF VENICE, CALIFORNIA.

PORTABLE READING DESK.

Application filed January 3, 1923. Serial No. 610,429.

To all whom it may concern:

Be it known that I, RUSSELL R. WADE, a citizen of the United States, residing at Venice, in the county of Los Angeles and 5 State of California, have invented new and useful Improvements in Portable Reading Desks, of which the following is a specification.

My invention relates to portable reading 10 desks adapted to serve as a valise for the carrying of literature and other articles and also as a stand or rack upon which a plurality of books or pamphlets may be supported in an open condition, in order that a person 15 in the pursuance of study or other investigation, may conveniently and readily refer from one book to another; and is particularly adapted for the use of Christian Science students where frequent reference 20 from the quarterly pamphlet of Bible lessons, containing sermons and citations, to the Holy Bible and the Science and Health publication is necessary.

It is the primary object of my invention 25 to provide a simple, convenient and durable portable desk or stand for the above described purpose, having book rests thereon arranged so that the three publications may be disposed in a manner most convenient to 30 the student.

Another object of my invention is to provide a desk which may be used as a receptacle for the convenient carrying of the various publications desired, said desk being 35 provided with a suitable carrying handle which may be so adjusted as to form a convenient support for one of the publications, and also may be adjusted out of sight when the desk is laid aside and not in use.

40 The above and other objects of my invention will be more fully set forth in the following specification, reference being had to the accompanying drawings, is which:

Fig. 1 is a perspective view of a desk embodying my invention, showing the desk handle in adjusted position to serve as a support for one of the publications.

Fig. 2 is a transverse section through the same.

50 Fig. 3 is a transverse section through the top portion of the desk showing the handle as it would appear when the desk is being transported from one place to another.

55 Fig. 4 is a similar view to that of Fig. 3 showing the handle out of utility.

Fig. 5 is a fragmental section taken on the line 5—5 of Fig. 3.

In carrying out my invention, the desk comprises an enclosed receptacle formed of the end walls 10, the top 11, the bottom 12, 60 the rear wall 13, and the front wall 14, said front wall comprising the stationary member 15 and the door 16 hinged thereto at its top edge by means of the hinges 17. The top 11 is narrower than the bottom 12 thus disposing the front wall 14 at an angle which inclines rearwardly and upwardly, in order that the publications may be supported thereon at a convenient reading angle. The lower edge of the door 16 is provided 65 with an outwardly projecting ledge 18 upon which the lower edges of the books rest and in order that they may be placed properly and prevented from shifting sideways, the notches 19 are provided in the upper surface of the ledge for the reception of the book back.

The combined foldable book rest and carrying handle 20, comprises a pair of oppositely disposed side bars 21, between the outwardly projecting ends of which the cross bar handle 22 is secured. The free ends of the side bars 21 project through slots 22', formed in the top 11, and are provided with elongated slots 23 for the reception of a hinge rod 24 which is secured to the under surface of the top 11 by means of screws or nails, as clearly shown in Fig. 5 of the drawings.

90 By the above described construction it will be obvious that when it is desired to utilize the member 20 as a book rest, (as shown in Figs. 1 and 2 of the drawings), the side bars 21 are moved downwardly until the upper end edges of the slots 23 engage with the hinge rod 24, and are inclined rearwardly until the front edges of said side bars engage with the front edges 25 of the slots 22. Thus the member 20 will be held in position to act as a book rest; and in order that the book may be prevented from sliding therefrom, the ledge 26 is provided and is secured to the front edge of the top 11 in front of the member 20.

100 When the member 20 is to be utilized as a handle, it assumes the position shown in Fig. 3 of the drawings, and when not in use it is folded downwardly with the side bars 21 disposed in the slots 22 as shown 110 in Fig. 4 of the drawings.

By the above recited construction of reading desk, it will be apparent that a person pursuing the study of the Christian Science religion may place the quarterly pamphlet 5 in position on the rest 20, as shown in dotted lines at 27, the Bible in the position shown in dotted lines at 28, and the Science and Health pamphlet in the position shown at 29, and thus refer from one to the other of 10 these publications in a very convenient manner.

What I claim is:

A portable reading desk, comprising a receptacle having one of its sides arranged

on an incline and having formed on its top 15 a pair of transversely disposed slots, a combined book rest and handle provided with side bars projecting in the slots of the desk top and having slots formed in their inwardly projecting ends, and a hinge rod 20 passing through the slots in the side bars of the combined book rest and handle secured to said desk.

In witness that I claim the foregoing I have hereunto subscribed my name this 15th 25 day of December, 1922.

RUSSELL R. WADE.
